Wakefield, Mass., a corporation of Massachu-
sets

Application August 30, 1948, Serial No. 46,756

13. Claims. (Cl. 291—29)

1

This invention relates to sanders for vehicles such as motor vehicles, and aims to provide an improved shut-off arrangement which prevents sand leakage, and to provide an improved stirrer to promote the flow of sand to and through a spout or conduit from the hopper to the outlet. The invention will best be understood by reference to the following description when taken in connection with the accompanying drawings of one specific embodiment thereof, while its scope will be pointed out more particularly in the appended claims.

In the drawings:

Fig. 1 is a fragmentary perspective view of a motor truck with a sander mounted adjacent one of its dual wheels, the sander being partly broken away to disclose the mechanism more particularly the subject matter of the invention;

Fig. 2 is a plan of a portion of the hopper bottom and the sander mechanism carried thereby;

Fig. 3 is a front elevation, partly in vertical section;

Fig. 4 is a vertical section on line 4—4 on Fig. 3;

Fig. 5 is a vertical section on line 5—5 on Fig. 3;

Fig. 6 is a vertical section on line 6—6 on Fig. 3;

Fig. 7 is a wiring diagram for a six-volt circuit; and

Fig. 8 is a wiring diagram for a twelve-volt circuit.

In Fig. 1 there is shown a portion of a truck having mounted on its frame adjacent the wheels 3 a hopper 5 for sand or other grit from which the grit is dispensed by the mechanism more fully disclosed in the other figures and forming the subject matter of the present invention. The operation of this mechanism is electrically controlled from a position convenient to the driver, which, broadly considered, is conventional in installations of this kind. Grit is delivered when desired from the hopper 5 and passes through spouts 7 to the ground immediately in front of the wheels. No novelty is claimed in the general structure as so far described. In the case of a truck having dual rear wheels, it is desirable that the sander be dual.

Referring now to the other figures of the drawings and beginning the description of the embodiment of the invention illustrated therein as an example, the mechanism (other than the electric control switch 30 to be referred to and the wiring) may be organized on a plate 8 which forms a part of the bottom of the hopper 5.

Sand or other grit supplied from the hopper is discharged through a member in the nature of a conduit 10, presently to be described, the outlet

2

of which is controlled by a shut-off 12 in the nature of a valve-cup below and close to the outlet of the conduit, and which traverses said outlet and which contains a small amount of sand remaining from the last discharge forming therein a sand seal for the conduit. In opening and closing the conduit there is no sliding or rubbing action, in fact, there is no contact of the valve-cup 12 with the conduit 10. Thus the valve-cup, so called, differs from the usual valve or valve-head that cooperates with a valve-seat by making sealing contact therewith. To this end, the conduit 10 is provided with a flexible skirt 14, in the nature of a length of a rubber tube, applied to and about the conduit 10, and depending therefrom (see Fig. 4), but spaced slightly from the valve-cup 12 and conforming to the shape of the latter.

In the present instance, the valve-cup 12 is cylindrical, in part, open at the top, and has closed ends, one of which is affixed as by a screw 16 threaded into the end of a shaft 18 which turns in bearings 20 affixed to brackets 22 attached to the supporting plate 8. The shaft 18 is rotated, at will, as by mechanism such, as for example, that shown at Fig. 6, including a solenoid 24 comprising an armature 26 movable within a coil 28 housed in a housing 30 affixed to the top of the plate 8. The armature 26 projects through the plate 8 and has affixed to it a yoke 32 having a slot 34 within which there is a pin 36 on a crank-arm 38 affixed to the shaft as by a locking piece 40 spot-welded to the crank arm 38 and embracing flats 42 on the shaft 18. In this example, the shaft 18 turns through an angle, as, for example, 90°, in response to an impulse furnished to the coil 28. The "down" or "open" position is shown in Fig. 6.

Returning now to the conduit 10 (see Fig. 4) the latter is rigidly affixed, as by spinning at 44, to the plate 8, the latter forming at least a part of the bottom of the hopper for the sand. Associated with the inlet of the conduit 10, there is a stirrer lever 48 extending above the inlet of the conduit 10 to promote the flow of sand from the hopper to the outlet of the conduit. This stirrer 48 is in the present instance operated by the valve-cup 12. The latter, to this end, is provided with a shoulder 50 to strike a shoulder 52 on the stirrer 48, thereby to cause the latter to move in the region of the inlet of the conduit 10. The stirrer 48 is mounted between its ends on the plate 8, as by a movable mount 54, herein in the nature of a block of rubber about the stirrer and extending through the plate 8 and clamped to the plate

by a clamp 56. The plate 8 has a hole 58 and the clamp 56 has a hole 60, through which the stirrer 48 extends to furnish a resilient mounting, thereby to prevent contact of the stirrer 48 except through the cushioning action of the rubber mount 54. In this instance, the stirrer 48 curves laterally above and in line with the inlet of the conduit 10 to influence the stream of sand as it approaches the inlet. The actuating portion of the stirrer below the plate is relatively short and a relatively slight range of movement thereof produces a considerable movement of the actuating portion above the plate and received in the body of sand. As will be apparent from Fig. 3, the movement of the curved over end of the stirrer will have a substantial reciprocation vertically directly above the inlet to the conduit and will thus operate with as a blade which has a pumping action effective to force sand to and through the conduit, breaking up obstructions caused by interengagement of granules in a more or less coherent, self-maintaining structure. If desired, the stirrer 48 may have a depending portion 62 affixed to or loosely attached to its upper portion above the inlet of the conduit 10. If desired, the shoulder 52 may have a second function, namely, to strike the conduit 10 to promote the flow of the sand through the conduit 10 and least on the initial opening movement of the cup 12 when it moves against shoulder 52 with considerable momentum.

In addition to the described mechanism, the stirrer 48, the latter has other means to cause the same to vibrate under the influence of an electric circuit (see Fig. 7) while the valve-cup 12 remains away from the outlet of the conduit 10. This circuit is controlled by an arm 64 (see Fig. 5) affixed to the shaft 18 and having a striker 66 adjustably mounted on the arm, as by a screw 68 extending through the arm. The arm 64 is adjustably mounted on the shaft 18, as by a screw 70 passing through the shaft and having a nut 72 and lock-nut 74. As the arm swings upwardly, the striker 66 strikes a switch 76 included in a circuit (see Fig. 7, or Fig. 8) now to be described, affixed to the supporting plate 8 (see Fig. 5).

The circuit (see for example, Fig. 7) includes a battery 78 (in this case 6 volt), the current being controlled by a control switch 80 operated by hand or foot. The coil 28, associated with the armature 26, is operated by switch 76 associated with a suitable condenser 82. The switch 76 is a single-pole, single-throw, with normally closed contacts. One such switch, called "Micro" is made by Micro Switch Company, of Freeport, Ill., under Pat. No. 2,170,748. The arrangement is that there is a repeating cycle in the circuit so long as the control switch 80 remains closed by the operator. In other words, when the control switch is closed, it energizes the solenoid, thus causing the armature to rise, and actuating the sander mechanism; then, at the instant the mechanism reaches the end of the travel, it actuates the vibrator switch 76, breaking the circuit. This permits the armature 26 to drop back, thus causing the switch 76 to close, reclosing the circuit. The armature 26 is drawn up, once more, and the cycle is repeated so long as the operating switch 80 remains closed. In operation, the current is actually flowing about half the time, because the circuit is continually opened and closed. Therefore, instead of drawing 7 amperes continuously, it is drawing 7 amperes only half the time, which gives an average current flow, during the period of operation, of only 3½ amperes.

Some trucks are provided with a 12 volt battery (see Fig. 8) in which case the circuit is modified to the extent that one-half of the voltage of the battery is used for two solenoids. In Fig. 6 the 5 solenoids are connected in parallel, in Fig. 7 in series. The three dots shown in the figures adjacent the switches 83 are points of connection existing in a commercial switch as above identified which permit such alternate methods of 10 wiring. In each instance one of them is not used.

There are many advantages, (1) the stirrer in the form shown serves to form an "arch" over the inlet of the conduit and prevents packing of the sand, (2) in the opening action the valve-cup 15 taps the stirrer, causing it to move sharply among the massed grits, causing them to flow, (3) when the initial opening action is completed, the arrangement described causes repeated oscillation of the valve-cup throughout a small range 20 adjacent its open position while the discharge end of the conduit remains fully open. This is communicated to the lower end of the stirrer, and the end of the stirrer above the base plate is given a relatively great reciprocating movement 25 having a substantial vertical component toward and away from the inlet end of the conduit, producing a pumping action to drive the sand into and through the conduit. This continues while the cup is in the open position, (4) the relationship 30 of the lower end of the stirrer to the outlet of the conduit may be such that, when the stirrer is struck by the valve-cup, at least in the initial opening movement when the cup has substantial momentum, the lower actuating end of the stirrer 35 will be driven against the side of the conduit to strike a percussive blow effective to start into motion the column of sand in the conduit, (5) the flexible mounting of the stirrer lever provides a loose pivot so that when its lower end is struck 40 by the valve-cup it operates as a lever, its upper end moving through a relatively long path as described, (6) the continual "make" and "break" action reduces the mean current consumption from 7 amperes on a continuously closed circuit 45 to 3.5 amperes, (7) the flexible skirt on the outlet of the conduit allows the valve-cup to open and to close with a minimum of friction or drag from the grits, (8) without the flexible skirt on the outlet of the conduit, the following will result:

50 (a) If the rigid tube is extended far enough toward the valve-cup to prevent leaking of the grits, the latter will jam or wedge between the valve-cup and the tube and prevent the valve-cup from opening.

55 (b) If a rigid outlet tube be shortened enough to prevent jamming of grits, the valve-cup will open when it should, but the grits will leak from the hopper when the vehicle is driven over a rough road.

60 (c) The clearance between the rigid tube and the valve-cup which would be necessary in order to accomplish either of the above purposes varies with each and every different grit size, whereas, with the flexible skirt, this is not a factor, and

65 (9) for any given size of outlet conduit or tube there is a limit to the size of grit which will flow through it by gravity alone, because of the tendency of larger grits to crowd at the entrance to the outlet conduit. When this happens, the grits 70 will form an arch and cease flowing. This tendency is greatly reduced by the action of the stirrer.

Having described one embodiment of the invention, what I claim is:

75 1. In a road sander for vehicles of the type

having a depending discharge conduit for the gravity discharge of sand, a cup mounted adjacent the outlet end of the conduit having a closed position beneath but spaced from said outlet end providing for the accumulation of sand therein to seal the outlet and an open position laterally removed from the conduit, means for moving the cup between open and closed positions, the combination therewith of a stirrer having a portion extending above the inlet end of the conduit and a portion extending into the path of movement of said cup, a support for said stirrer, means to effect a reciprocation of the stirrer with at least a substantial vertical component of movement of said portion toward and from the inlet of said conduit when the cup moves to open position and cooperating means effective while the cup is in open position to effect repeated like reciprocations.

2. In a road sander for vehicles of the type having a depending discharge conduit for the gravity discharge of sand, a cup mounted adjacent the outlet end of the conduit having a closed position beneath but spaced from said outlet end providing for the accumulation of sand therein to seal the outlet and an open position laterally removed from the conduit, means for moving the cup between open and closed positions, the combination therewith of a stirrer having a portion extending above the inlet end of the conduit and a portion projecting into the path of movement of the cup, a resilient support for the stirrer, and means operated consequentially to the movement of the cup to, and effective while it is in, open position, to effect repeated oscillations of the cup through a small range adjacent its open position to cause it repeatedly to strike the stirrer to effect reciprocating movement of the stirrer with at least a substantial vertical component of movement of said portion toward and from the inlet of the conduit.

3. The combination of claim 1 wherein the cup has a portion which as the cup travels to open position moves toward the side of the conduit and transmits a percussive blow thereto.

4. In a sander for vehicles a base plate having a discharge conduit depending therefrom for the gravity discharge of sand, a closure member having a closed position beneath the outlet end of the conduit and an open position remote therefrom, a stirrer lever, a flexible mounting on the plate laterally of the conduit for said lever, said lever having a relatively short actuating portion beneath the plate in the path of movement of said closure member, and an actuated portion extending above the plate and curved over and above the inlet end of the conduit in spaced relation thereto and means operated consequentially to the movement of the closure member to, and effective while it is in, open position, to effect repeated oscillations of the actuating portion of the stirrer lever and corresponding reciprocations of the actuated end thereof including vertical component toward and from the inlet of the conduit.

5. In a sander for vehicles a base plate having a discharge conduit depending therefrom for the gravity discharge of sand, a closure member having a closed position beneath the outlet end of the conduit and an open position remote therefrom, a stirrer having a sand-moving blade portion positioned over and above the inlet end of the conduit, a resilient mounting for said stirrer, and means including an offset portion of said stirrer normally positioned in the path of movement

of the closure towards open position operable when, and effective while, the cup is in open position to effect repeated oscillations of said blade with substantial vertical components toward and from the inlet of the conduit.

6. The combination of claim 5 wherein said blade has an extension depending therefrom and entering the conduit.

7. In a road sander for vehicles of the type having a depending tubular discharge pipe for the gravity discharge of sand therethrough, and a cup mounted adjacent the pipe having a closed position beneath but spaced from the outlet end thereof providing for the accumulation of sand therein to seal the outlet and an open position laterally removed from the discharge end of the pipe, the combination with said pipe of a depending skirt of flexible material constituting in effect a continuation of the pipe, the lower end of the skirt opposing but being spaced from the inner wall of the cup when the latter is in closed position.

8. In a road sander for vehicles of the type having a depending tubular discharge pipe for the gravity discharge of sand therethrough, and a cup mounted adjacent the pipe having a closed position beneath but spaced from the outlet end thereof providing for the accumulation of sand therein to seal the outlet and an open position laterally removed from the discharge end of the pipe, the combination with said cup and pipe of a tubular member of freely flexible material mounted on one of said parts and in the closed position of the cup being concentric with the pipe, with its end spaced from the other part.

9. In a road sander for vehicles of the type having a depending discharge conduit for the gravity discharge of sand, a cup mounted adjacent the outlet end of the conduit having a closed position beneath but spaced from said outlet end providing for the accumulation of sand therein to seal the outlet and an open position laterally removed from the conduit, means for moving the cup between open and closed positions, the combination thereof with a stirrer having a vertically extending body portion, resilient means supporting the body portion of said stirrer for oscillatory movement in a vertical plane, said stirrer having a portion at one side of its mounting extending into the path of movement of the material traveling through said conduit, and a portion below its mounting normally positioned in the path of movement of said cup, whereby the cup upon movement will engage the portion of the stirrer below the mounting to produce oscillatory movement of same in the material and in the plane of movement of the material.

10. The structure of claim 9 characterized in that the stirrer has its upper end bent into a position immediately above the inlet of the conduit and its lower end immediately adjacent the conduit for receiving the impact of the moving cup.

11. The structure of claim 9 characterized in that the resilient mounting provides a pivotal point for the stirrer adjacent its point of contact with the cup, and the upper portion of the stirrer which oscillates in the traveling material is spaced substantially from the pivotal point to thereby provide for multiplication of movement due to engagement of the cup with the depending portion of the stirrer.

12. The structure of claim 9 characterized in that the resilient mounting is in the form of a rubber pad which embraces and supports a por-

tion of the vertically extending body portion to effect repeated oscillations of the stirrer after initial movement.

13. In a road sander for vehicles of the type having a depending discharge conduit for the gravity discharge of sand, a cup mounted adjacent the outlet end of the conduit having a closed position beneath but spaced from said outlet end providing for the accumulation of sand therein to seal the outlet and an open position laterally removed from the conduit, means for moving the cup between open and closed positions, the combination therewith of a stirrer having an end portion extending above the inlet end of the conduit, and a depending offset end portion normally positioned in the path of movement of said cup, and a resilient mounting for said stirrer supporting the same intermediate its ends for oscillatory movement in a vertical plane, whereby engagement of the cup with the depend-

ing portion of the stirrer will effect movement of the same towards and away from the inlet of the conduit.

JAMES W. COVENEY.
